UNITED STATES PATENT OFFICE.

EDWARD A. UEHLING, OF NEWARK, AND ALFRED STEINBART, OF CARLSTADT, NEW JERSEY.

PNEUMATIC PYROMETER.

SPECIFICATION forming part of Letters Patent No. 639,317, dated December 19, 1899.

Application filed August 4, 1897. Serial No. 647,025. (No model.)

To all whom it may concern:

Be it known that we, EDWARD A. UEHLING, a citizen of the United States, and a resident of Newark, in the county of Essex, and ALFRED STEINBART, a native of Germany, (but having declared in due form my intention of becoming a citizen of the United States, and possessing official papers from the German Government that I am no longer a subject of the German Emperor,) residing at Carlstadt, in the county of Bergen, State of New Jersey, have invented certain new and useful Improvements in Pneumatic Pyrometers, of which the following is a specification.

This invention relates to improvements in pneumatic pyrometers, and especially to improvements in the pneumatic pyrometers for which United States Letters Patent No. 11,413, reissued April 17, 1894, and No. 554,323, issued February 11, 1893, were granted to us.

The object of our invention is to simplify the construction, to render the instrument more effective and reliable, so that it requires less attention and care.

In the accompanying drawings, forming a part of this specification, and in which like letters of reference indicate like parts in all the views, Figure 1 is a side elevation of our improved pyrometer. Fig. 2 is a front elevation of the same and a longitudinal view of the fire-tube. Fig. 3 is a central vertical sectional view of the upper part of the apparatus on an enlarged scale. Fig. 4 is a longitudinal sectional view of the fire-tube. Fig. 5 is a detail sectional view of the apertured disk. Fig. 6 is a vertical detailed sectional view of the suction device.

The vertical cylindrical body A is provided with a base A'. To the front of said body A an upright supporting-arm B is bolted at the top and is provided at about two-thirds of its height with a bend or flat offset portion B' toward the rear, to which portion B' a pot C is bolted which is closed at the bottom and is closed at the top by a suitable cover C'. A head C² is formed on the upper end of the arm B, and from the same a central web or ridge C³ extends down the entire length of the arm on the front, conforming to the configuration of the face of the arm. A metal plate D, on the face of which a proper pyrometric scale

is produced, is fastened longitudinally to the front of the vertical body and is provided along each longitudinal edge with a flange D', the lower ends of said flanges and said plate 55 extending to a bracket D² on the front of the body, into which bracket a glass jar D³ is screwed from the bottom. The jar has a cover D⁴, from which a gage-rod D⁵ extends down into the jar.

The pyrometric or temperature scale may be produced on the plate D in any suitable manner by printing, casting, or engraving, or it may be printed on a strip of paper pasted on said bar.

The base A' of the body A has a neck a provided with a stop-cock a', and the outer end of said neck is connected with a cross a², from which a tube b extends up to the bottom of the pot C and is in communication with the 70 interior of said pot.

Two glass tubes E and F are placed against the inner sides of the flanges D' of the plate D and in such a manner that the tube F is directly in front of the scale, and said glass 75 tubes pass through openings in the cover D⁴ into the jar D³ to near the bottom of the same. The upper ends of the glass tubes E and F are held by suitable packing-couplings c in the head C² on the arm B. The upper end of 80 the glass tube E is connected by said coupling c and the metal tube E' with the upper part of the hollow body A or "regulator," as it will now be designated. The upper end of 85 the glass tube F is connected by its coupling c and the tube F' with a chamber H, projecting laterally from the upper part of the pot C and having its outer end closed. A recording-gage G of any suitable construction is brought in communication with said chamber 90 either directly, as shown, or it may be located a greater or less distance away and connected with said chamber by a tube. The chamber H is also connected by a tube H' with the platinum tube which is to be inserted into the furnace, heater, &c., of which the temperature is to be determined and which platinum tube will be described in detail hereinafter. A filter W' is formed in said chamber. It serves to protect the fine parts 95 of the instrument in case the air-conducting tube system breaks.

A neck J, projecting laterally from the upper part of the pot C, contains a suction device, such as a steam-operated aspirator or injector of any desired construction, such as are usually provided for producing suction for the purpose of delivering water into boilers, &c.; but in this case this well-known suction device is only to be used for producing a partial vacuum, and said neck is provided with a coupling J' for connecting a steam-pipe with the said neck J. A tube K, having a cock K', connects the neck J with the upper part of the regulator A.

L is a filling-neck for the regulator.

15 A coiled pipe M in the pot C connects the chamber H with the neck I and pipe I', leading from the pot C to top of regulator A.

A tube N, open at the top and bottom, is secured in the top of the regulator and extends 20 down to near the bottom of the same, thus forming a substantially U-shaped vessel having two legs of greatly-different diameter and in communication with each other at their lower ends.

25 In the neck I a copper or other metal disk m is clamped, and in the same a finely-aper-tured platinum disk O is held, aperture x' being one of the apertures in a system of pipes or chambers to be referred to hereinafter. 30 The other fine aperture x is formed in the closed end of a platinum tube P, surrounded by a larger platinum tube R, also closed at the outer end. The inner ends of the platinum tubes P and R are attached to the copper tubes P' and R', respectively. The other end of the tube P' is secured in one end piece of a cup P², having a neck P³, to which is connected the tube H', leading to the chamber H on the pot C. The cup P² is filled with 40 loose cotton-batting up to a screen P⁴, and thus is a filter for the air passing through the pipe system. One end of the cup P² is en-larged to form one end of an additional but larger cup Q, in the opposite end of which the 45 inner open end of the tube R' is held. In said cup Q two wire screens Q² are secured near the ends and the space between the cups is filled with cotton-batting to form a filter. R² is an air-inlet aperture for the cup Q. A

50 water-jacket S of suitable construction is formed on the head Q' and surrounds part of the tube R' and is provided with the inlet and outlet necks S' S² for the cooling-water. The platinum tubes just described are in-55 serted into a furnace, hot air or gas main, or into any other heated space the temperature of which is to be determined. The outer air entering through the inlet-opening R² passes through the filtering-screens Q² and the cot-60 ton-batting in the cup Q and through the tubes R R' to the minute aperture x in the end of the inner platinum tube P, into said tube P, to the cup P² through the cotton-batting in the same, and to the neck P³ and tube 65 H' to the chamber H. From the same, as well as through the above-mentioned tubes, it is drawn by suction in the regulator A through

the coil M, in the pot C, and through the ap-erture x' and the tube I' into the regulator. From the latter it is drawn by the aspirator 70 through the pipe K and conveyed into the pot C, from which it passes off with the waste steam, drip water, &c., through the pipe b.

The operation is as follows: Live steam is admitted to the aspirator or like suction de-75 vice in the neck J, and the exhaust or waste steam that has operated the aspirator escapes into the pot C. As the neck J, in which the aspirator is located, is in connection with the upper part of the regulator A by the pipe K, 80 the suction produced by the aspirator forms a partial vacuum in the regulator, and this vacuum is maintained by means of the aspi-rator at a certain predetermined height of water-column shown in the glass-tube E. In 85 consequence of this suction the atmosphere enters the filter Q and passes through the pipe system described to the aperture x, and before entering the same it attains the tem-perature to be determined and enters the 90 pipe system through the aperture x at this temperature, and finally before leaving the pipe system through the aperture x' this air is brought or cooled to 212° while passing through the coil M, which is surrounded by 95 the exhaust-steam in the pot, and is thus maintained at a temperature of 212° as the aspirator discharges its exhaust-steam into the pot, as stated above. The temperature remaining constant at the outlet-aperture x', 100 the change in tension of the air in the pipe system between the apertures x x' depends upon the changes in temperature at the inlet-aperture x, and as the changes of tempera-ture affect the tension of air in the regulator 105 A the column of water in the glass gage-tube F rises or falls correspondingly, and if a re-cording-gage is used affects the same corre-spondingly.

Having now described our invention, what 110 we claim as new, and desire to secure by Let-ters Patent, is—

1. In a pneumatic pyrometer, the combina-tion with an upright vessel for containing water, of an upwardly-extending arm on the 115 same, a pot held by said arm and a pipe sys-tem having apertures at its ends, which pipe system is connected with the upper part of said upright vessel and part of which system passes through said pot and a glass gage-120 tube containing a water-column and in com-munication with said pipe system, substan-tially as herein shown and described.

2. In a pneumatic pyrometer the combina-tion with a vessel for containing water and 125 divided longitudinally into two chambers of which one is closed and the other communi-cates with the air, of a pot, a suction device connected with the upper end of the closed chamber of said vessel and with the pot, a pipe system having apertures at its ends and connected beyond the part between the aper-tures, with the upper part of the closed cham-130 ber of said vessel and a glass gage-tube con-

- nnected with said pipe system between the apertures and a jar into which said gage-tube dips, substantially as herein shown and described.
- 5 3. In a pneumatic pyrometer the combination with an upright vessel, divided longitudinally into two chambers of which one is closed at the top and the other open to the air, of a pot, a suction device in communication with said pot and with the closed chamber of said vessel, a coil in said pot, an apertured disk at the outlet end of said coil, a pipe connecting said outlet end with the closed chamber, a pipe system connected with the inlet end of the coil and having an inlet-aperture at its opposite end, a glass gage-tube connected with said pipe system between the apertured ends and a jar into which the lower end of said gage-tube dips substantially as herein shown and described. 45
- 10 4. In a pneumatic pyrometer, the combination with a pipe system having an inlet and an outlet aperture, a suction-chamber connected with the said pipe system; a suction device connected with said chamber and a water-gage tube connected with said pipe system between the apertured ends and a water-jar into which said gage-tube dips substantially as herein shown and described. 50
- 15 5. In a pneumatic pyrometer, the combination with an upright vessel, of an upwardly-projecting arm on the same, a pot secured to said arm, a plate secured to said upright vessel and having longitudinal flanges, glass tubes placed on the front of said arm and flanged plate, a pipe system having apertured ends, with which pipe system one of said glass tubes is connected the other being connected with the top of the upright vessel, and 55
- 20 a suction device for producing suction in said upright vessel and in the pipe system and a water-jar into which the lower ends of said pipes are dipped substantially as herein set forth. 55
- 25 6. In a pneumatic pyrometer the combination with a pipe system having end apertures, of a water-gage glass tube connected with said pipe between the said end apertures, a pot for heating part of said pipe system at one of the apertures uniformly and a steam suction device for producing a circulation of air in said pipe system, which steam suction device discharges into the pot for heating part of said pipe system substantially as herein shown and described. 60
- 30 7. In a pneumatic pyrometer the combination with a pipe system having apertures, of a device for conveying air through said pipe system by steam; and means for heating part of said pipe system at one of the apertures by the exhaust-steam of said steam-operated air-conveying device and an indicator connected with said pipe system, substantially as herein shown and described. 65
- 35 8. In a pneumatic pyrometer the combination with a pipe system having apertures of a steam - operated device for conveying air through said pipe system, a pot through which part of said pipe system passes and into which said steam-operated device discharges its exhaust and an indicator connected with said pipe system, substantially as herein shown and described. 70
- 40 In testimony that we claim the foregoing as our invention we have signed our names in presence of two witnesses. 75
